(57) **CLAIM**

I claim the ornamental design for a grill removal tool, as shown and described.

DESCRIPTION

FIG. 1 is a perspective view of a grill removal tool showing my new design;

FIG. 2 is a first side elevation view of the grill removal tool of FIG. 1;

FIG. 3 is a second side elevation view of the grill removal tool of FIG. 1;

FIG. 4 is a top plan view of the grill removal tool of FIG. 1;

FIG. 5 is a bottom plan view of the grill removal tool of FIG. 1;

FIG. 6 is an elevation posterior view of the grill removal tool of FIG. 1; and

FIG. 7 is an elevation anterior view of the grill removal tool of FIG. 1.

FIGS. 8-14 show a second embodiment of a grill removal tool showing my new design.

FIG. 8 is a perspective view of a grill removal tool showing my new design;

FIG. 9 is a first side elevation view of the grill removal tool of FIG. 8;

FIG. 10 is a second side elevation view of the grill removal tool of FIG. 8;

FIG. 11 is a top plan view of the grill removal tool of FIG. 8;

FIG. 12 is a bottom plan view of the grill removal tool of FIG. 8;

FIG. 13 is an elevation posterior view of the grill removal tool of FIG. 8; and,

FIG. 14 is an elevation anterior view of the grill removal tool of FIG. 8.

The broken lines portions of the grill removal tool form no part of the claimed design.
